COMBINED CONSOLE AND DESK FOR A COMPUTING MACHINE

Elmer J. Stoltz, Alameda County, Calif., assignor to Friden, Inc., a corporation of California

Filed Dec. 28, 1959, Ser. No. 58,838

Term of patent 14 years

(Cl. D26—5)

FIG. 1

FIG. 5

FIG. 1 is a perspective view of a combined console and desk for a computing machine embodying the design of the present invention.

FIG. 2 is a top view thereof.

FIG. 3 is a front elevation thereof.

FIG. 4 is a right elevation thereof, and

FIG. 5 is a rear elevation thereof.

The left-facing side, not shown, of the cabinet-like portion at the right of the device consists of two simple framed panels, one above the table-like portion, and one below it, and so is similar to the right-facing side, shown.

The back of the cabinet-like portion and the back of the panel on the table-like portion are conventional as shown.

The dominant features of my design reside in those portions shown in full lines on the drawing.

I claim:

The ornamental design for a combined console and desk for a computing machine, as shown and described.
